DESIGN FOR A SPAT

Herbert S. Rauh, New York, N. Y.

Application December 16, 1943, Serial No. 112,014

Term of patent 7 years

(Cl. D7—7)

To all whom it may concern:

Be it known that I, Herbert S. Rauh, a citizen of the United States of America, residing at New York, in the county of New York and State of New York, have invented a new, original, and ornamental Design for Spats, of which the following is a specification, reference being had to the accompanying drawing, forming a part thereof, and wherein

Fig. 1 is a side elevational view of a spat showing my new design, and

Fig. 2 is a front elevational view of such spat.

The essential features of my design for a spat as shown reside in the flap closure which is positioned wholly to one side of the spat, is substantially rectangularly-shaped so that the three button holes thereof and cooperating buttons are arranged in a substantially straight row, one above the other, and which is of such length that it extends up the spat to a point approximately midway of its height and defines the front of the por-

tion of the spat body which is of greatest width or depth; the fur trim which extends around the upper edge of the spat in the manner shown to a point immediately above the line of juncture of the flap closure with the spat body; the type of bow lacing shown; the rear of the spat which in the upper portion of the body curves inwardly and merges into a relatively straight line which starts at a point approximately level with the top of the flap and extends to the bottom of the body and which is disposed at an acute angle to the bottom edges of the body; and the bottom edges of the spat which are substantially straight and horizontal except where they merge into the transverse lines of the strap and conform at the front of the spat with the bottom edge of the closure flap.

I claim:

The ornamental design for a spat, substantially as shown.

HERBERT S. RAUH.
